(57) **CLAIM**

The ornamental design for a stylus, as shown and described.

DESCRIPTION

FIGS. 1 and 2 are perspective views of a stylus, showing our new design, according to a first embodiment thereof.

FIG. 3 is a first side view of the stylus, according to the first embodiment.

FIG. 4 is a second side view of the stylus, according to the first embodiment.

FIG. 5 is a third side view of the stylus, according to the first embodiment.

FIG. 6 is a top plan view of an end of the stylus, according to the first embodiment.

FIG. 7 is a bottom plan view of the other end of the stylus, according to the first embodiment.

FIG. 8 is a perspective view of the stylus, according to the first embodiment.

FIGS. 9 and 10 are perspective views of the stylus, showing our new design, according to a second embodiment thereof.

FIG. 11 is a first side view of the stylus, according to the second embodiment.

FIG. 12 is a second side view of the stylus, according to the second embodiment.

FIG. 13 is a third side view of the stylus, according to the second embodiment.

FIG. 14 is a top plan view of an end of the stylus, according to the second embodiment.

FIG. 15 is a bottom plan view of the other end of the stylus, according to the second embodiment; and,

FIG. 16 is a perspective view of the stylus, according to the second embodiment.

Subject matter shown in broken lines is environmental and forms no part of the claimed embodiments in which the broken lines appear. However, Applicants reserve the right to claim any combination or subset of subject matter, whether shown in broken lines or solid lines, in this application or in one or more divisional applications thereof.

All shade lines show contour and not surface ornamentation.
